CLAIM

The ornamental design for footwear as shown and described.

DESCRIPTION

FIG. 1 is a perspective view of footwear, showing our new design.

FIG. 2 is a front view of the footwear of FIG. 1.

FIG. 3 is a back view of the footwear of FIG. 1.

FIG. 4 is a side view of the footwear of FIG. 1.

FIG. 5 is another side view of the footwear of FIG. 1, from the opposite side as shown in FIG. 4.

FIG. 6 is a top view of the footwear of FIG. 1; and,

FIG. 7 is a bottom view of the footwear of FIG. 1. The broken lines surround portions of the footwear that form no part of the claimed design.
